UNITED STATES PATENT OFFICE.

ROLO D. HILL, OF LOS ANGELES, CALIFORNIA, ASSIGNOR OF ONE-HALF TO NELLA H. HILL, OF LOS ANGELES, CALIFORNIA.

CONTAINER.

Application filed March 22, 1926. Serial No. 96,557.

My invention is a container intended for use particularly in marketing bottled goods or the like in which the container forms a protective wrapping and also comprises a 5 circular or the like descriptive of the goods.

An object of my invention is to form a container to be used in selling bottled goods such as proprietary medicines or the like, in which a descriptive circular is wound 10 around the bottle and pasted together, forming a covering, this covering being closed by caps inserted over the ends of the cover so formed and secured preferably by gluing or the like.

15 A further object of my invention is to form a descriptive circular with preferably a covering material and provide this with a glued edge so that when the circular is wound around the bottle the edge may be 20 glued forming a tight covering to which the caps may be attached.

My container is preferably suited to round bottles so that when the circular is wound on the bottle it forms a cylinder. One of 25 the covers of the circular or additional covering sheets is slightly longer than the main part of the circular or pamphlet so that the edge may be glued. A corrugated cardboard forming a protection for the neck of 30 the bottle is inserted in one end of the container and caps are fitted over the capped circular forming closures for each end.

35 My invention will be more readily understood from the following description and drawings, in which;

Figure 1 is a perspective view of my container in its completed form.

Fig. 2 is a vertical section taken substantially on the line 2—2 of Fig. 1, showing the 40 container with a bottle therein.

Fig. 3 is a horizontal section on the line 3—3 of Fig. 2.

Fig. 4 is a perspective view of the circular or pamphlet rolled into a cylinder and secured by a glued edge.

Fig. 5 illustrates in perspective, a preferred way of making the circular or pamphlet with a removable cover forming the outside of the finished package.

50 My invention is particularly adapted for the merchandising of bottled goods in which a bottle is indicated by the numeral 1 having a base 2, side walls 3, a shoulder 4 and a neck portion 5 with a cap 6. It is pref-

erable to use circular bottles when my type 55 of container is utilized.

The container structure is formed from a pamphlet or descriptive circular designated by the numeral 7 and particularly shown in Fig. 5. This circular preferably 60 has a number of printed pages 8 of descriptive matter of the particular goods contained in the bottle or other suitable matter and has front and back cover sheets 9 and 10. The whole pamphlet is preferably secured together by staples 11 in the usual manner.

It is desirable to have one of the cover leaves slightly longer than the other as indicated by the numeral 12, this extension having glue or cement or the like formed 70 thereon to be utilized as hereunder set forth. I find it desirable to make the covers of waxed tissue paper so that the advertising matter on the outside of the pamphlet may be read through such paper. However, this 75 is optional. One of the reasons for using the extra cover sheets is so that these may be torn off if they are mutilated before the goods are opened.

The circular or pamphlet is rolled around 80 the bottle forming a cylindrical wrapping such as shown in Fig. 4; this figure indicating the bottle as being removed or if desired the circular may be rolled on a mandrel having substantially the same size as the 85 bottle. The circular is then cemented at the portion indicated by the numeral 13 in Figs. 1 and 4. After the circular is rolled on the bottle the corrugated end section 14 formed of corrugated cardboard or the like is inserted in the end preferably resting on the shoulders 4 of the bottle or if the bottle is inserted after the circular is rolled, this corrugated portion may subsequently be inserted. The lower and upper caps 15 and 90 16 are then fitted over the ends of the circular. These caps preferably have a flat side 17 and a flange 18 being thus cup-shaped. The flanges are preferably glued to the outside cover of the pamphlet or circular, thus forming a substantial while compact container with the advertising matter included.

It is usual where bottled goods especially such as proprietary medicine are marketed 105 in cartons to include either advertising circulars or other matter descriptive of the use of the drug. With my container it is not

necessary to use a carton, thereby reducing the bulk of the package and eliminating the cost of the outside container.

It will be apparent that my container may 5 be utilized for other shape bottles than round, it merely being necessary to have the caps of the proper shape to fit the rolled descriptive circular after being wrapped on the bottles. The container may be utilized 10 for many other kinds of packages than bottled goods, these being taken as an illustration as the covering, circular or pamphlet forms a protection for the bottles or other article contained therein.

15 Although my invention is of a simple character, it will nevertheless be apparent that it may be modified in general construction or in specific details to suit different uses of my container. Such changes however, would be within the spirit of my invention as set forth in the description, drawings and claims.

It will be noted by reference to Figs. 1 and 2 that the flanges 18 of the caps are of 25 such thickness that they increase the diameter slightly over that of the center portion of the wrapping. Therefore when bottles or the like packed in my container are loaded 30 in a shipping case the flanges are in contact and the main portion of the wrapper out of contact. Hence there is no danger of breakage of the bottles.

Having described my invention, what I claim is:

- 35 1. In combination a bottle or other receptacle, a container formed of a wrapping of a plurality of sheets, said sheets being in the form of a circular or pamphlet, the edge of one of the sheets being cemented 40 to the outside of the container, and caps secured on opposite ends of the wrapped circular or pamphlet forming end closures.
2. In combination a bottle or other re-

ceptacle, a container formed of a circular or pamphlet comprising a plurality of 45 leaves, staples securing said leaves in one end, the free end of one of the outside leaves being cemented to the outside of the wrapped circular or pamphlet, and caps having flanges, the flanges being cemented to the 50 outside of the circular or pamphlet forming end closures.

3. In combination a bottle or other receptacle, a container therefor comprising a circular or pamphlet having descriptive sheets 55 and an outside cover adapted to be destroyed, the circular or pamphlet encircling the bottle, the edge of one of the outside cover leaves being cemented to a portion of one of the outside cover leaves, and caps having flanges fitted over the end of the encircling circular or pamphlet, the flanges being cemented to the outside removable cover.

4. A container comprising a circular or pamphlet having a plurality of descriptive 65 leaves and cover sheets, said pamphlet being rolled into a wrapping and having one edge of one of the cover leaves cemented to part of the cover and caps forming end closures for the container, said caps being cemented 70 to the cover sheets.

5. A container comprising a circular or pamphlet having a descriptive leaf and an outside destructible cover sheet, the cover sheet being longer than the descriptive leaf, 75 said circular or pamphlet being wound on itself into a roll and having the long end of the cover leaf cemented to the rolled circular or pamphlet and closure caps having flanges on each end of the rolled circular 80 or pamphlet, the flanges being cemented to the outside destructible cover sheet.

In testimony whereof I have signed my name to this specification.

ROLO D. HILL.
